INVENTOR:

Harry M. Collester
of High Point, North Carolina
Myself

UNITED STATES PATENT OFFICE.

HENRY M. COLLESTER, OF GARDNER, MASSACHUSETTS.

DESIGN FOR CANE FABRIC.

SPECIFICATION forming part of Design No. 26,549, dated January 19, 1897.

Application filed December 11, 1896. Serial No. 615,406. Term of patent 7 years.

To all whom it may concern:

Be it known that I, HENRY M. COLLESTER, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design consists in the arrangement of polygonal-shaped figures *a* and *b*, crossed by interrupted stripes 15 *c* of contrasting color, the design appearing to the eye of the observer as a series of raised figures on a checked or striped background.

f represents a piece of cane fabric bearing my design, which consists of the polygonal-shaped figures *a* and *b*, the latter arranged 20 within the former, and the interrupted stripes *c* of contrasting color.

I claim—

The design for cane fabric, as herein shown and described.

In testimony whereof I have signed my name to this specification, in the presence of two subscribing witnesses, this 30th day of November, A. D. 1896.

HENRY M. COLLESTER.

Witnesses:

EDWARD G. WATKINS,
THATCHER B. DUNN.
